(57) CLAIM

The ornamental design for a red sole and midsole assembly for a single-sole shoe, as shown and described.

DESCRIPTION

The file of this patent contains at least one drawing executed in color. Copies of this patent with color drawing(s) will be provided by the Office upon request and payment of the necessary fee.

FIG. 1 is a perspective view of a red sole and midsole assembly for a single-sole shoe shaded to show the color red, showing our new design;

FIG. 2 is a first side view thereof;

FIG. 3 is a second side view thereof;

FIG. 4 is a top view thereof;

FIG. 5 is a bottom view thereof;

FIG. 6 is a front view thereof;

FIG. 7 is a back view thereof;

FIG. 8 is a perspective view of another embodiment of our new design of a red sole and midsole assembly for single-sole shoe of FIG. 1, illustrated in conjunction with a disclaimed shoe upper, where the red portions are indicated using the USPTO convention of solid vertical and horizontal cross-hatched lines for red or pink;

FIG. 9 is a first side view thereof;

FIG. 10 is a second side view thereof;

FIG. 11 is a top view thereof;

FIG. 12 is a bottom view thereof;

FIG. 13 is a front view thereof; and,

FIG. 14 is a back view thereof.

The broken lines showing elements in the above described Figures are for illustrative purposes only and form no part of the claimed design.
